UNITED STATES PATENT OFFICE.

JAMES M. MOODY AND SIDNEY B. MOODY, OF HARWICH, MASSACHUSETTS.

ICE HARVESTING OR CUTTING MACHINE.

SPECIFICATION forming part of Letters Patent No. 433,953, dated August 12, 1890.

Application filed May 2, 1890. Serial No. 350,346. (No model.)

To all whom it may concern:

Be it known that we, JAMES M. MOODY and SIDNEY B. MOODY, citizens of the United States, residing at Harwich, in the county of Barnstable and State of Massachusetts, have invented a new and useful Ice Harvesting or Cutting Machine, of which the following is a specification.

This invention has relation to ice harvesting or cutting machines; and the objects in view are to provide a machine so constructed and arranged as to uniformly cut the blocks of ice, said machine being simple and economical in construction and easy of operation.

Various other minor objects of the invention will hereinafter appear, and the novel features will be particularly pointed out in the claims.

Referring to the drawings, Figure 1 is a perspective of an ice-cutting machine constructed in accordance with our invention. Fig. 2 is a bottom plan view. Fig. 3 is a central longitudinal section looking toward the traction-wheel. Fig. 4 is a front elevation. Fig. 5 is a detail in perspective of one of the depending supporting standards or knees and the gage. Fig. 6 is a detail in perspective of the portion of the periphery of the traction-wheel. Fig. 7 is a detail in perspective of the saw-elevating yoke and the gears for operating the same.

Like numerals of reference indicate like parts in all the figures of the drawings.

1 designates the platform of the machine, upon which is located the seat 2 for the operator. The platform is provided with a depending surrounding frame 3, to which there is connected removably the mechanism-supporting frame 4 of rectangular or oblong shape. The frame 3 is provided with a series of hooks 5, pivoted thereto, which take into eyes or keepers 6, projecting from the frame 4. The lower frame 4 is provided with a longitudinally-disposed beam 7, and upon the under sides of the beam 7 and the two side bars of the frame 4 there is located a pair of aligning bearing-boxes 8, in which is mounted for free movement a shaft or axle 9. In rear of the boxes 8 there is mounted upon the under side of one of the bars 8 and beam 7 a pair of aligning boxes 10.

Mounted loosely upon the axle or shaft 9 is a traction-wheel 11, provided at one side with a driving-gear 12, also loose upon the shaft, and beyond said drive-gear there is keyed to the shaft a pinion 13.

Between the opposite bar of the frame and the beam 7 upon the shaft or axle 9 there is loosely mounted a pair of hangers 14, in the free ends of which is journaled a shaft or arbor 15, upon which is fixed the ice-cutting saw 16 and a pinion 17. Opposite the pinion 17 upon the shaft 9 there is mounted a large gear 18, which engages and drives the pinion, said gear being fixed or rigid upon the shaft or axle 9.

In the boxes 10 there is mounted a short transverse shaft 19, fixed upon which is a small pinion 20 and a large gear 21, said small pinion meshing with the drive-gear 12 and the large gear 21 meshing with the small pinion 13, before mentioned.

The periphery of the traction-wheel is provided with a series of radiating teeth 22, the rear walls of which are beveled, as at 23, and between the teeth the periphery of said wheel is oppositely inclined, as at 24, so that no accumulations of snow, ice, or slush can occur.

To the under side of the front and rear end bars, at their opposite ends, are secured L-shaped knees or depending standards 25, braced by diagonal braces 26, and provided upon their upper sides near their ends with bearing-eyes 27. Those knees or standards 25 at that side of the frame in which is located the ice saw or cutter are longer and project farther from the machine than do those at that side of the machine at which is located the traction-wheel, and said longer standards 25 are provided at their lower extremities with shoes or runners 28. When in motion, one side of the machine is supported by the traction-wheel and the opposite side by the said shoes or runners 28. Upon the outer faces of the depending portions of the L-shaped standards are located vertically-opposite pairs of headed studs 29, and mounted upon the studs for vertical reciprocation are guide or gage plates 30, vertically slotted, as at 31, to receive the shanks of the studs. The plates are extended at one side, as at 32, at one side of the machine, and at the opposite side extended in an opposite direction, and in said exten-

sions or projections are pivoted, as at 33, the lower ends of connecting-rods 34. Mounted in the bearing-eyes before mentioned, upon each pair of laterally-opposite standards, is a 5 crank-shaft 35, each of said shafts terminating at its ends at the ends of the standards in oppositely-disposed cranks 36, which have their ends pivotally connected to the upper ends of the connecting-rods, so that when one 10 pair of cranks at one side of the machine is depressed the opposite pair at the opposite side is elevated, and with them the guide-plates of the standards. Each of the crank-shafts is provided between its bearings and 15 at one side of the machine with similarly upwardly-disposed crank portions 40, said portions being connected by a longitudinally-disposed rod 41, which may be operated by the foot of the operator from his seat.

20 The shaft or arbor 15, upon which is mounted the ice-cutting tool, is loosely journaled at its ends in an inverted-U-shaped yoke 42, the upper end of the yoke projecting through an opening 43 in the platform of 25 the machine and pivotally connected, as at 44, to a hand-lever 45, which is pivoted at its front end in a bearing-eye 46, and is provided at its opposite or free end with a keeper 47, loosely embracing a toothed and curved 30 standard 48, secured to the platform. The lever has also pivoted thereto a pivoted locking-bolt 49, whereby the operating-lever may be raised and lowered and adjusted at any 35 desired position, and during said raising and lowering will raise and lower the ice-sawing tool and its supporting hangers.

In operation the machine is drawn along by horse or other power, and the mechanism for cutting the ice operated by the rotations 40 of the traction-wheel. The traction-wheel is loose upon the shaft and the pinion 13 and gear 18 rotated by reason of the train of gearing described much more rapidly, which speed is further increased by transmission to 45 the pinion 17 and the saw-arbor, so that an exceedingly slow rotation of the traction-wheel causes an exceedingly rapid rotation of the saw 16. The depth of cut of the saw 16 is conveniently regulated by the raising and 50 lowering of the operating-lever before mentioned, and also said saw may be raised entirely from contact with the ice, as when the machine is traveling from one field of ice to another. After the first cut has been made 55 the lower curved ends of the guide-plates of those standards having the shoes or runners are projected by the operator through the medium of the crank-shafts to points below said standards, and are entered into the saw- 60 kerf just formed, and the machine proceeds back to the starting-point, and after such point is reached is turned for a new cut and the crank-shafts oscillated to withdraw the guide-plates last in action and project the 65 opposite pair of guide-plates beyond the lower ends of the opposite pair of standards, so that they will take into the kerf formed upon

the return trip and ride in the same during the formation of a new cut. In this manner it is apparent that each successive cut is precisely parallel with the remaining cuts and in cross-sawing exactly square cakes of ice are produced.

It will be observed that the machine at all times rests upon the traction-wheel and the 75 two runners, which runners, being located at a distance from the side of the machine, serve to throw the major portion of the weight of the machine upon the traction-wheel.

From the above description it will be apparent that we have provided a most rapid and accurate ice-cutting machine, of simple and cheap construction, and capable of producing uniformly-proportioned cakes of ice, whereby the latter may be snugly stored with 85 a great saving of room.

Having thus described our invention, what we claim is—

1. In an ice-cutting machine, the combination, with a frame and a journaled shaft, of 90 a traction-wheel and gear loosely mounted on the shaft and a gear rigidly mounted on the shaft, a second shaft journaled at one side of the main shaft and provided with a pinion meshing with the gear and a gear meshing 95 with the fixed pinion of the main shaft, a gear fixedly mounted upon said main shaft, a pair of swinging hangers located at the sides of the gear, an arbor mounted in the ends of the hangers, a saw fixed upon the arbor, a pinion 100 fixed upon the arbor at one side of the saw and engaging the last-mentioned gear, and means for raising and lowering said hangers, substantially as specified.

2. In an ice-cutting machine, the combination, with a frame, of a shaft mounted therein, and a second shaft mounted in rear of the first shaft, of a traction-wheel and gear loosely mounted upon the first shaft, and a pinion and gear fixedly mounted upon said 110 shaft, a pinion and gear fixedly mounted upon the second shaft, the pinion engaging the loose gear of the first shaft and the gear of the second shaft engaging the fixed pinion of the first shaft, a saw-arbor located at one side 115 of the first shaft, a pinion mounted on the same and engaging the fixed gear of the said shaft, and a saw mounted upon the arbor, substantially as specified.

3. In an ice-cutting machine, the combination, with the frame, of a shaft mounted thereon, a traction-wheel and fixed gear mounted on the shaft, hangers loosely mounted at their rear ends upon the shaft, an arbor journaled in the ends of the hangers, a pinion and saw 125 mounted upon the arbor, the former being driven by the gear of the shaft, an operating-lever pivoted on the frame-work and connected to the arbor, and means for locking said lever, and gearing for transmitting motion from the traction-wheel to the shaft, substantially as specified.

4. In an ice-cutting machine having a circular saw and means for operating the same,

the combination, with a pair of standards arranged at one side of the machine and gage-
plates mounted for reciprocation upon the standards, of means for raising and lowering
5 said gage-plates above and below the ends of the standards, substantially as specified.

5. In an ice-cutting machine, a pair of gage-
plates mounted for vertical reciprocation at
10 the sides of the machine and mechanism for
raising and lowering said plates into and out
of contact with the ice, substantially as specified.

6. In an ice-cutting machine, the combination, with the same and the cutting mechanism, of a pair of L-shaped standards depending from the frame and terminating in shoes or runners, slotted plates mounted upon the standards, headed studs projecting from the standards and serving as guides for the plates,
15 and means for raising and lowering said plates above and below the shoes, substantially as specified.

7. The combination, with an ice-cutting-machine frame, of pairs of depending L-
20 shaped standards projecting from the opposite sides of the frame and provided with guide-plates mounted for sliding thereupon and crank-shafts journaled above the stand-

ards and terminating in oppositely-disposed cranks, each of which is loosely connected 30 with a guide-plate, substantially as specified.

8. In an ice-cutting machine, the combination, with the frame and the opposite pairs of depending L-shaped standards provided with vertically-opposite headed studs, of longitudinally-slotted guide-plates mounted for movement upon the studs, transversely-disposed shafts arranged over each pair of said standards, each of said shafts terminating at its opposite ends in cranks oppositely disposed 35 to each other and provided with intermediate cranks, which latter cranks of the two standards are disposed in the same direction, connecting-rods connecting each of the outer cranks with a guide-plate and a longitudinally-disposed connecting-rod connecting the two intermediate cranks, substantially as specified.

In testimony that we claim the foregoing as our own we have hereto affixed our signatures 40 in presence of two witnesses.
